UNITED STATES PATENT OFFICE.

DWIGHT B. LEE, OF CHICAGO, ILLINOIS.

DESIGN FOR A WHEEL.

SPECIFICATION forming part of Design No. 29,826, dated December 20, 1898.

Application filed November 22, 1898. Serial No. 697,200. Term of patent 7 years.

To all whom it may concern:

Be it known that I, DWIGHT B. LEE, a citizen of the United States, residing at Chicago, in the county of Cook and State of Illinois, 5 have invented and produced a new and original Design for Wheels, of which the following is a specification, reference being had to the accompanying drawings, forming a part thereof.

- Figure 1 is a plan view of a wheel embodying my new design. Fig. 2 is a sectional view of the same, taken on dotted line $x-x$ of Fig. 1.

As shown in the drawings, the leading or material feature of my design consists in the 5 form and direction of the spokes of the wheel, they being so arranged as to leave a space A, of diamond form, between each spoke. The plan view of these spokes is substantially of Y form, the upper members B of the Y being

somewhat widespread and the stem C of the Y radiating from the hub of the wheel. The angle between the two upper members B of the Y in each spoke is filled in concentric with a circular opening D, occurring at the juncture of the members of the Y. The upper ends of the Y join the rim of the wheel, forming between them a figure E of substantially triangular outline. One face of this wheel is plane, while on the other face the hub and the rim rise above the surface of the 30 spokes.

I claim as my invention—

The design for a wheel substantially as herein shown and described.

DWIGHT B. LEE.
